UNITED STATES PATENT OFFICE.

PAUL D. BERNARD, OF NEW YORK, N. Y.

LEATHER OR SWEAT-BAND FOR STRAW HATS.

1,192,375.

Specification of Letters Patent. Patented July 25, 1916.

Application filed March 15, 1916. Serial No. 84,270.

To all whom it may concern:

Be it known that I, PAUL D. BERNARD, a citizen of the United States, and a resident of the city of New York, borough of Brooklyn, county of Kings, and State of New York, have invented a new and useful Improvement in Leather or Sweat-Bands for Straw Hats, of which the following is a specification.

10 The invention relates to the manufacture of straw hats, and is more particularly concerned with the leathers or sweat bands thereof. Heretofore such leathers have been cut straight, and, though "sprung in", have not been substantially more conforming to the head than the rigid character of the hat would permit; consequently it has been difficult to obtain a good fit, and the hat, bearing upon the head only at certain points and 20 there with a substantially unyielding pressure, has displayed a disagreeable tendency to ride up.

In accordance with this invention the hat proper is made over-size, and the leather is 25 cut on a curve and united to the hat in such manner as to form a pronounced basal bevel, whereby substantially the entirety of the leather stands away from the hat and is enabled to conform itself to the head, which is 30 clasped with a uniformly distributed cushion-like pressure, insuring a satisfactory fit and overcoming the tendency to ride.

In the accompanying drawings illustrating the invention: Figure 1 is a view of the 35 leather before insertion in the hat, the leather being shown spread out flat and its ends broken away because of the limitation of space; Fig. 2 is a similar view of the pad which is employed; Fig. 3 is a vertical section through the hat with the leather attached, the pad being still in place; and Fig. 4 is a similar view, the pad being removed.

The straw hat proper, designated 1, may be produced by any suitable or usual procedure, but is made over-size, that is to say, if the hat, when completed, is to fit a seven head and to be sold as a number seven hat, its straw will be made of a size which would

ordinarily be a seven and an eighth. The leather band 2, instead of being cut straight, 50 as usual, is curved, its base 3 being curved out, and its upper edge 4 being curved in. This leather is sewed by its base to the bottom of the inside of the crown of the hat, and a pad 5 is employed to give the leather 55 the desired basal formation and to cause it to stand away from the straw. This pad may be made of various suitable materials, of which felt may be mentioned as an example, is of a thickness sufficient to produce 60 the result desired, and of a length to extend substantially around the interior of the crown, though in practice its ends may be separated more or less. This pad is preferably inserted between the leather and the 65 hat prior to the sewing of the sweat-band to the straw, though this may be varied. After or even during the sewing, the operator exerts pressure with the fingers upon the leather, straining and shaping it over the 70 pad, so that the leather is given a permanent set at the base, as shown in Figs. 3 and 4, this formation being in the nature of an abrupt bevel or curve 6, which sets the entirety 75 of the body of the sweat-band substantially away from the interior of the crown. The pad is then removed, leaving the hat and its band possessed of the characteristics and advantages already set forth.

What is claimed as new is:

In the manufacture of straw hats, the 80 steps which comprise, providing an over-size hat, providing a leather cut on a curve substantially throughout its length, introducing the leather and a pad into the hat, sewing the convex basal edge of the leather to the hat, working the base of the leather over said pad so as to produce a basal bevel, and removing the pad.

In witness whereof, I have hereunto set 90 my hand this 10th day of March, 1916.

PAUL D. BERNARD.
